UNITED STATES PATENT OFFICE.

HENRY W. NEWMAN, OF NEW YORK, N. Y.

DESIGN FOR AN ADVERTISING-KIOSK.

48,867.

Specification for Design.

Patented Apr. 11, 1916.

Application filed January 23, 1915. Serial No. 4,057. Term of patent 7 years.

To all whom it may concern:

Be it known that I, HENRY W. NEWMAN, a citizen of the United States, residing at New York city, in the county of New York, State of New York, have invented a new, original, and ornamental Design for an Advertising-Kiosk, of which the following is a specification, reference being had to the accompanying drawing, forming part thereof.

The figure is a perspective view of an advertising kiosk showing my new design.

I claim:

The ornamental design for an advertising kiosk, as shown.

HENRY W. NEWMAN.

Witnesses:

R. L. CONRAD,
HERBERT J. CARROLL.
